H. Everts & Co
Seth's

UNITED STATES PATENT OFFICE.

FREDREK KUMBER, OF PITTSBURG, PENNSYLVANIA.

SWITCH-THROWING MECHANISM.

SPECIFICATION forming part of Letters Patent No. 673,657, dated May 7, 1901.

Application filed January 11, 1901. Serial No. 42,855. (No model.)

To all whom it may concern:

Be it known that I, FREDREK KUMBER, a citizen of the United States of America, residing at Pittsburg, in the county of Allegheny and State of Pennsylvania, have invented certain new and useful Improvements in Switch-Throwing Mechanism, of which the following is a specification, reference being had thereto in to the accompanying drawings.

10 This invention relates to certain new and useful improvements in switch-operating devices, and has for its object to provide novel and effective means whereby the switch may be conveniently operated by the motorman 15 without dismounting from or stopping the car.

The invention is particularly adapted for use in connection with street-railways; and it comprises a box or casing adapted to be embedded in the track adjacent to the switch-tongue and provided with a projecting table or plate forming a guide for the operating-shoe carried by the car. The box or casing has a shaft journaled in the same, and mounted on this shaft is a spur-gear or cog-wheel, 25 which operates through a slot in the top or cover of the box or casing. Movement is imparted to this spur-gear or cog-wheel and through it to the shaft within the box or casing by a shoe carried by the car, and the degree of movement imparted to the cog-wheel and shaft upon each engagement of the shoe with the cog-wheel is limited by means of an incline arranged on top of the box or casing, so that the shoe will be forced out of engagement with the cog-wheel after having actuated the latter a sufficient distance to move the switch-tongue through its connections therewith. The switch-tongue carries a downwardly-extending pin that operates through 35 a slot in the box or casing, this pin extending downwardly into the box or casing, with a spring pressing against the same to hold the switch-tongue normally closed. The shaft within the box or casing carries a cam or

45 clutch for engagement with the pin as the shaft is operated to actuate the switch point or tongue, all of which construction will be hereinafter more specifically described and then particularly pointed out in the claims.

50 In describing the invention in detail reference will be had to the accompanying drawings, forming a part of this specification, and

wherein like numerals of reference indicate similar parts throughout the several views, in which—

55 Figure 1 is a top plan view of a portion of a road-bed and track, showing the switch-operating mechanism in position. Fig. 2 is a longitudinal sectional view thereof, taken on the line 2 2. Fig. 3 is a transverse vertical 60 sectional view thereof, taken on the line 3 3 of Fig. 1. Fig. 4 is a detail perspective view of the box or casing for the mechanism and guide-table for the shoe carried by the car. Fig. 5 is a transverse vertical sectional view 65 of a part of this box or casing, showing a part of the shaft and the clutch or cam for operating the switch-tongue.

To put my invention into practice, I arrange in the road-bed 1 a box or casing 2, 70 closed at the top, sides, and ends, but which may, as shown, be open at the bottom and preferably constructed with end flanges 3, so that the road-bed may be laid directly thereon to hold the box or casing firmly in the bed. 75 The top of the box or casing though closed is so made by means of a removable lid 4, which rests upon an interior flange or ledge 5. This box or casing is located in the road-bed adjacent to the switch-tongue and has at 80 one end the forwardly-extending plate or table 6, supported at the outer end by the downwardly-turned end 7 and flange 8.

A part of the box or casing, as at 9, projects in under the frog 11, the latter lying 85 directly upon the part 10 of the box or casing, and this frog is provided with a slot 12, which registers with a like slot 14 in the part 10 of the box or casing. The switch-tongue 15 carries a pin 16, which extends downward through 90 the slots 12 14 into the box or casing and is held so as to retain the switch-tongue normally against that side of the frog in which the switch will be in the closed position by means of a spring 17, connected to said pin 95 and to the inner face of the box or casing.

The box or casing has within the same a downwardly-extending bracket 18, and journaled in this bracket and in one side wall of the box or casing is a shaft 18', extending 100 transversely to the track, with a spur-gear or cog-wheel 19 mounted thereon, that projects upwardly through a slot 20 in the lid or cover 4 of the box or casing. Arranged adjacent

to this slot 20 upon the lid or cover 4 are inclined walls 21, the specific purpose of which will be hereinafter explained. The shaft 18' carries on its free end a clutch or cam 22 for engagement with the pin 16 as the shaft is rotated and move said pin and the switch-tongue to actuate the latter as desired.

Suspended from the car-platform 23 is a shoe 24, this shoe operating through the said platform and being held normally elevated by means of a coil-spring 25, arranged between the car-platform and the head 26 on the upper end of the shoe. This shoe is adapted to be of sufficient width to engage both of the inclined walls 21 at the sides of the slot 20 in cover or top 4 of the casing 2.

In operation when it is desired to move the switch from the closed position, as shown in Fig. 1, to the open position, so that the car 20 may pass onto the side track, the motorman depresses the shoe 24 as he approaches the table or plate 6, the shoe riding on the smooth surface of this plate or table until it comes in contact with the spur-gear or cog-wheel 19, 25 which it engages sufficiently long to move said wheel one tooth, which distance is sufficient to actuate the shaft 18 and turn the cam or clutch member 22 into position that the pin 16 of the switch-tongue will be opposite one 30 of the openings 22' in said cam or clutch member, into which opening the pin 16 will be forced by the action of its spring 17. The engagement of the shoe with the cog-wheel is limited by the inclined walls 21, as it will be 35 observed that when a movement sufficient to actuate the switch-tongue has been imparted to the cog-wheel the shoe will have engaged the inclined walls 21 and will by them be carried out of engagement with the spur-gear or 40 cog-wheel. In case the succeeding car desires to continue on the main track the engagement of the shoe with the cog-wheel will again actuate the shaft and cam or clutch member, so as to engage the latter with the

pin in the position shown in Fig. 5, and thus 45 again close the switch to the side track and permit the car to continue on the main track.

It will be noted that in the construction of a switch mechanism in accordance with my invention various changes could be made in 50 the details of construction without departing from the general spirit of my invention.

Having fully described my invention, what I claim as new, and desire to secure by Letters Patent, is—

1. In a device of the character described, the combination with the switch-tongue, a downwardly-extending pin attached to its under face, a shaft mounted in the road 2, a cog-wheel mounted on said shaft, a cam member 60 carried by said shaft engaging said pin of the switch-tongue, a spring, arranged on the opposite side of said pin, normally retaining the switch-tongue in a closed position, a means suspended from the car adapted to operate 65 said cog-wheel, substantially as described.

2. In a device of the character described, the combination with the switch-tongue, the pin carried by said switch-tongue, a spring engaging said pin for holding the switch-tongue normally in the closed position, of a box or casing having a removable lid or cover provided with a slot, a shaft journaled in the box or casing, a cog-wheel mounted on said shaft and projecting through the slot in the lid or cover, 75 a cam or clutch member carried by the shaft for engagement with the pin of the switch-tongue, and means carried by the car for engagement with the cog-wheel to actuate the same and move the switch-tongue, substantially as described.

In testimony whereof I affix my signature in the presence of two witnesses.

FREDREK KUMBER.
